(57) **CLAIM**

The ornamental design for an equipment mount, as shown and described.

DESCRIPTION

FIG. 1 is a front, right, top perspective view of an equipment mount showing the new design;

FIG. 2 is a rear, left, bottom perspective view thereof;

FIG. 3 is a front elevation view thereof;

FIG. 4 is a rear elevation view thereof;

FIG. 5 is a right side view thereof;

FIG. 6 is a left side view thereof;

FIG. 7 is a top plan view thereof;

FIG. 8 is a bottom plan view thereof; and,

FIG. 9 is an exploded perspective view thereof.

The broken lines of even-length shown in the drawings illustrate portions of the equipment mount that form no part of the claimed design.
